BALANCED IMPELLER FOR CENTRIFUGAL PUMPS

Thomas W. Johnson, Parsippany, N. J., assignor to Bendix Aviation Corporation, Teterboro, N. J., a corporation of Delaware

Application November 22, 1949, Serial No. 128,813

2 Claims. (Cl. 103—103)

1

The present invention relates to centrifugal pumps and particularly to means and methods for balancing the axial reactive forces on the impellers thereof.

The action of the impeller during the operation of the pump is to hurl the fluid into the delivery chamber from the impeller chamber thereby causing a pressure gradient to exist about the impeller. The effect of this pumping action is to cause more fluid to flow into the pump casing, and as the action of the impeller is continuous, the pressure gradient above-mentioned remains continuously across the impeller. Because of the difference in area of the face of the rear shroud and the face of the front shroud of the impeller, the impeller and shaft are subjected to an undesirable axial thrust.

It is, therefore, one of the objects of the present invention to provide a novel method of balancing the impeller means whereby the foregoing disadvantage is eliminated, and to do so in a novel and effective manner.

Another object of the invention is to provide an impeller for a centrifugal pump whereby several of the power losses now present are eliminated.

Another object of the invention is to provide an impeller for a centrifugal pump whereby shallow grooves of a specified size and number on the rear of the shroud act as non-delivering centrifugal pumps so as to create a pressure on the shroud to balance the other fluid forces thereon.

Still another object of the invention is to provide a balanced impeller for a centrifugal pump thereby obviating the necessity for thrust bearings on the impeller.

Another object of the invention is to balance the forces on the impeller of a centrifugal pump in such a manner to permit a shorter overall pump length.

Still another object of the invention is to increase the efficiency of a centrifugal pump by eliminating the energy losses caused by the longitudinal pull on the impeller.

Still another object of the invention is to provide means of the above-indicated character which shall be simple and economical to manufacture and install, yet positive and reliable in operation.

The foregoing and other objects and advantages will appear more fully hereinafter from a consideration of the detailed description which follows, taken together with the accompanying drawings, wherein one embodiment of the inven-

2

tion is illustrated by way of example. It is to be expressly understood, however, that the drawings are for the purpose of illustration only, and are not to be construed as defining the limits of the invention.

Referring to the drawings wherein like reference characters designate like parts,

Fig. 1 is an elevation partly in section of a centrifugal pump assembly.

10 Fig. 2 is a perspective view of the impeller, rear face upwards.

Fig. 3 is a view showing the relative magnitude of the unbalanced areas of the impeller.

15 Referring now to the drawings and more particularly to Fig. 1, a centrifugal pump generally designated by the numeral 10 comprises a casing 12 and inlet 14 and outlet 16. The casing 12 contains an impeller chamber 18, having front and rear walls 19 and 21, respectively, and where- 20 in the impeller 20 is free to rotate, driven by the shaft 22 which is coupled to the source of rotary power 24. Casing 12 also contains an outlet chamber 18a peripherally disposed about impeller chamber 18 and communicating therewith. The seal 26 of the shaft 22 is considerably smaller in diameter than inlet conduit 28, which difference contributes to the unbalance of the axial loads on the impeller as hereinafter explained. A seal 25 encompasses the shaft 22 and prevents leakage from the chamber 18. The impeller 20 includes a front shroud 32 and a rear shroud 34 held together by pins 35. Vanes 37 are provided in the rear shroud 34 and open from the interior of the impeller 20 to the chamber 18 and outlet chamber 18a.

30 During normal operation of the pump, a clearance space A between the front shroud 32 of the impeller and the front wall 19 of impeller chamber 18, and a clearance space B between the rear shroud 34 of the impeller and the rear wall 21 of chamber 18 are filled with fluid from the outlet chamber 18a and therefore, the shrouds 32 and 34 are subjected to pressure therefrom over the surfaces 36 and 38, respectively (Fig. 3).

35 Referring now to Fig. 2, the rear shroud 34 of the impeller 20 contains a series of relatively shallow slots 40 radially disposed about the periphery thereof and extending towards the shaft 22. The length L of the slots 40 is adjusted 40 as hereinafter explained depending upon the relative unbalance of the impeller.

45 Having thus explained the invention, it will now be apparent to those skilled in the art that when a fluid from the inlet 14 is drawn into the 50 impeller 20 and hurled against the walls of the

outlet chamber 18a for ejection through the outlet 16, all of the clearance space between the front shroud 32 and on the surface 38 of rear shroud 34. the rear shroud 34 and rear wall 21 of chamber 18 will become filled with fluid which will exercise a pressure on the surface 36 of the front shroud 32 and on the surface 32 of rear shroud 34.

Since the surface 38 is greater than the surface 36, partly because of the greater diameter of the inlet conduit 28 compared to the seal 26 of the shaft 22, the pressure on the rear shroud 34 would ordinarily be greater than the pressure on the front shroud 32 thereby causing an undesirable axial component in the direction of the inlet 14. However, the slots 40 in the rear shroud 34 impart a turning swirling action to the fluid between the face of the rear shroud 34 and the adjacent rear wall 19 of chamber 18, and in effect act as non-delivering centrifugal pumps, with the result that the total pressure on the rear shroud 34 is reduced tending to balance rather than overcome the pressure on the front shroud 32.

It is to be noted that the invention permits extremely finite balancing of the impeller forces since the shallow grooves 40 may first be cut of insufficient length L to balance the impeller, and the operation tested and then gradually increased in length L after each test run, thereby gradually approaching and ultimately reaching the precise balance point.

There are thus provided means for balancing the forces on the impeller of a centrifugal pump which are simple and economical to manufacture and yet positive and reliable in operation and which obviate the necessity for expensive thrust bearings.

It is further to be noted that the invention accomplishes the balancing of the impeller without the necessity of increasing the overall pump length since the fluid swirling means are contained within the impeller itself without protruding therefrom.

Although only one embodiment and one application of the invention has been illustrated and described, other changes in form and relative arrangements of the parts may be made to suit requirements.

What is claimed is:

1. In a centrifugal pump of the type including a casing, an impeller chamber in said casing having front and rear walls, an axial inlet in said front wall, an outlet including an outlet chamber peripherally disposed about said impeller chamber, and an impeller mounted for rotation in said impeller chamber, said impeller having front and rear shrouds arranged in spaced relationship with the front and rear walls of said impeller chamber and pumping vanes interposed between said front and rear shrouds, said inlet opening into the interior of said impeller whereby the rotation of said impeller pumps a fluid from said inlet to said outlet, and said impeller being effected by an unbalanced pressure distribution over the inner and outer surfaces of the front and rear shrouds upon

the pumping of a fluid as aforesaid, the improvement comprising a plurality of shallow grooves formed in the outer radial surface of said rear shroud opposite said inlet, said grooves extending radially inwards from the periphery of said rear shroud and effective upon the rotation of said impeller to rotate the fluid between said rear shroud and the wall of said impeller chamber adjacent said rear shroud whereby the rotational velocity of the rotating fluid is greatest adjacent the periphery of said rear shroud and the forces produced on the surface of said rear shroud by said rotating fluid are effective to balance the summation of all forces acting on the remaining surfaces of said impeller.

2. In a centrifugal pump of the type including a casing, an impeller chamber in said casing having front and rear walls, an axial inlet in said front wall, an outlet including an outlet chamber peripherally disposed about said impeller chamber, and an impeller mounted for rotation in said impeller chamber, said impeller having front and rear shrouds arranged in spaced relationship with the front and rear walls of said impeller chamber and pumping vanes interposed between said front and rear shrouds, said inlet opening into the interior of said impeller whereby the rotation of said impeller pumps a fluid from said inlet to said outlet, said rear shroud having a greater outer surface than the outer surface of said front shroud whereby a greater force is produced on said rear shroud upon rotation of said impeller to pump a fluid from said inlet to said outlet; the improvement comprising a plurality of radial grooves formed in the outer surface of said rear shroud, said radial grooves extending inwardly from the periphery of said rear shroud and terminating short of the center thereof, said radial grooves being effective upon the rotation of said impeller to produce a whirling of the fluid between said rear shroud and said rear wall to thereby produce a pressure distribution on the outer surface of said rear shroud decreasing proportionately from a high value adjacent the periphery of said radial grooves toward a lower value adjacent the inner ends thereof whereby the forces on the front and rear shrouds are equalized.

THOMAS W. JOHNSON.
